ATTORNEY

UNITED STATES PATENT OFFICE.

SAMUEL A. MEGEATH, OF NEW YORK, N. Y.

REFRIGERATOR BASKET.

Application filed June 15, 1927. Serial No. 199,049.

The object of this invention is, to supply a more convenient, efficient and sanitary refrigerator basket than those heretofore obtainable.

5 Nearly all baskets of this type are supplied with one or more compartments for ice, and one or more compartments for food, game, or fish, and so far as I am aware, none of them are provided with convenient means whereby 10 the water produced by the melting of the ice may be drained or otherwise emptied from the ice chambers.

Heretofore, it has been necessary to open the basket and pour this water out, and very often, 15 in so doing, it has also been necessary to remove the contents of the food compartment; this is not only very inconvenient, but many times, owing to the conditions under which such baskets must be used, it is also unsanitary, neutralizes the refrigeration and is wasteful of ice. Furthermore, it is particularly necessary to the proper preservation of the meat, game, fish or other food which forms the contents of the food chamber, that they be 20 kept as dry as possible, hence the ice compartment should be kept sufficiently free from water that it will not be likely to splash into the food chamber or form a humid atmosphere within the basket.

25 30 In order to provide a refrigerator basket which shall be as free as possible from objectionable features mentioned and to attain the desirable features set forth I have devised the basket shown in the accompanying drawings in which:

Fig. 1 is a plan view of the open basket with the food receptacle removed therefrom—handles shown.

Fig. 2 is a plan view of a basket having a 40 slightly modified form of bottom, and with the food chamber in position with its cover removed,—handles not shown.

Fig. 3 is a central, vertical, longitudinal section of my complete basket, the cover to the basket, and the cover to the food container both being shown in position but not in section.

Fig. 4 is a fragment of the bottom portion of the basket, having the form of bottom 45 shown in Fig. 1, the drain opening and its closure or cap being shown in section,

Fig. 5 is a half-plan view of the seat member of a drain-valve which may be substituted for the Fig. 4 form.

Fig. 6 is central, vertical section of the complete drain-valve of which Fig. 5 forms the seat and mounting member.

In detail, the construction shown in said drawings is substantially as follows:

In superficial form, outline and construction my improved basket may be of the usual type having the splint jacket 1, the inner lining of metal 2 and the intermediate insulation 3. A suitably constructed cover 4 is also provided; handles 5 are indicated in Fig. 1. Two 60 locator-rods 6, 6 are provided which extend across the interior of the basket, in proximity to the top thereof, and preferably positioned equi-distant from the ends of the basket. Said locator-rods are for the purpose of positioning and retaining the removable food container compartment 7 centrally—or preferably so—within the basket. Said food compartment is provided with a suitably constructed lid or cover 8. 75

Those portions of the interior of the basket adjacent each end thereof and indicated by the reference ordinal 9 are for the reception of ice for refrigeration purposes.

The bottom metal lining 2 of the basket is 80 provided with upwardly-extending ribs 10 or bosses 11, upon which the bottom of the food container rests; these features 10 and 11 serve as spacing means whereby the adjacent faces of said metal lining 2 and the bottom face 85 of the food container are spaced apart, as indicated by the reference ordinal 12, in Figs. 4 and 6, thus forming a free passage for water underneath said food container for a purpose presently to be set forth. 90

Located centrally of the bottom of the basket—or preferably at that position,—and extending therethrough is a drain port 13, which is adapted to be normally closed by any suitable device, such as a removable screw-threaded cap 14 as shown especially at Fig. 4, or by means of a valve 15 shown in Figs. 5 and 6.

The closure device for said drain-port 13 shown in Fig. 4 comprises the well-known 100 form of cooperating screw-threaded nozzle and cap 14, and when the water is to be

drained from the interior of the basket said cap 14 is removed, thus permitting the outflow of water through the drain port.

The construction and operation of the drain device shown in Fig. 6 is as follows: Into the bottom of the interior lining 2 of the basket is inserted and firmly secured the disk-like seat and carrying member 16 of this device. Said member 16 has on its upper face the seat portion 17 for the seating thereon of the knife-edge peripheral portion of the valve 15 within said seat portion of said disk. A plurality of outlet ports 18 are provided for the outflow of water from the ice chamber of the basket; the center of said seat disk is provided with a hole 19' for the passage and longitudinal movement of the valve stem 19. The under side of said seat member is provided with a centrally positioned, tubular portion 20, into which said stem 19 projects. The lower end of said valve-stem is threaded for the reception of a spring-compressing nut 21. Between said nut and the adjacent face of said seat member is interposed a compression spring 22 the reactive force of which may be so regulated by said nut as to hold the knife edge portion of the valve 15 into firm contact with its seat so as to form a leak-tight joint thereat. When water is to be drained from the ice chamber this drain-valve is opened by an upward pressure of the finger on the nut 21, so as to unseat the valve and permit water to flow therethrough. The function of the tubular portion 20 of said valve organization is, to form a guard for the stem 19, and its cooperating nut 21 whereby accidental opening of the valve is provided against. The knife-blade seating edge of this valve is provided so that it may be cheaply, quickly and easily ground to a perfect seat and for the further purpose of providing a narrow seat that is not likely to be prevented, by sediment and the like, from making a perfect seat upon and joint with its co-operating seat 16.

Another object of providing spacing features 11, of the elongated shape shown in Fig. 2, is to guide the water to the drain hole 13, when the basket is rocked or tilted, for the purpose of more effectually causing the drainage of water from the basket.

Reverting to the Fig. 4 form of this drain port, it will be noted that the lower face of the cap 14 when in its closed position is above the lower face of the floor—that is, the bottom—of the basket; the object of this construction is twofold, namely to provide an even face for the bottom of the basket so that it will set firmly upon a floor, table or the like; also to form a guard for said cap to prevent accidental displacement of or damage thereto.

Heretofore, refrigerator baskets have been constructed with a permanent food chamber

and a removable ice chamber, and with such a construction it is necessary to remove the ice chamber in order to empty the water therefrom, so as to prevent an excess of humidity of the air within the basket; such removal very materially lowers the refrigerating efficiency of the basket, increases the ice consumption and often necessitates the trouble and annoyance of removing a portion of the contents of the food chamber.

I claim the following:

1. A refrigerator basket, a portion of the interior chamber of which is adapted for the reception of ice, a drain-port leading through the bottom of said basket, ribs formed in the floor of said basket and radially disposed relative to said port so as to direct the flow of water thereto, and a food compartment removably positioned within said chamber having its lower face spaced from the bottom of said chamber by said ribs for the passage of water through the space thus formed to said drain port.

2. A refrigerator basket, the interior chamber of which is adapted to contain ice and to be partially filled therewith, a normally closed drain port leading through the bottom of said chamber, ribs formed in the floor of said chamber and radially disposed relative to said port, a food compartment removably carried within said ice chamber supported upon said ribs, and a closure member for said port actuatable to its open position for the drainage of water from said port.

3. In a refrigerator basket provided with a closely fitting cover; the combination thereof of a food container within and positioned centrally of said basket so as to form a plurality of ice chambers about said container also an intervening water space between the juxtaposed faces of the floor of said container and said basket, a normally closed drain device extending and projecting through the floor of said basket whereby water may be drained at will from said space, there being a countersunk housing in the floor wall of said basket surrounding the projecting portion of said drain device for the purpose set forth.

4. In a refrigerator basket, the combination of a removable food compartment positioned within the basket so as to form an ice chamber upon two opposite sides of said compartment also an intervening drainage space between the juxtaposed faces of the bottom of said food compartment and the floor of the basket chamber, a drain port in the floor of said basket in communication with said space, a drain device in said port projecting exteriorly of the basket, and a housing formed about the projecting portion of said device for the purposes specified.

5. In a refrigerator basket, the combination of a removable food compartment posi-

tioned within the basket so as to form a chamber for ice upon two sides of said food compartment also an intervening space between the adjacent faces of the bottom of said food compartment and the floor of the basket, there being a drain port through the floor of the basket in communication with said

space, a drain-valve organization in said port projecting through the floor, and a housing formed by said floor about the projecting portion of said organization, for the purposes specified. 10

In testimony whereof I affix my signature.
SAMUEL A. MEGEATH.
